(57) **ABSTRACT**

A match-insensitive low current bias circuit uses a transistor arrangement which takes advantage of the transistors' collector current degeneration, current gain through emitter sizing, and voltage gain to minimize any errors caused by stage mismatches created during production. The bias circuit of the present invention is particularly suited to integrated circuit applications where a low biasing current is required.

MATCH-INSENSITIVE LOW-CURRENT BIAS CIRCUIT

BACKGROUND OF THE INVENTION

1. Field of the Invention

The present invention relates to low current bias circuits. In particular, the present invention relates to low bias current sources in integrated circuit applications.

2. Description of the Related Art

Biassing techniques which are used in discrete circuit applications are not normally suited for use in integrated circuits. In an integrated circuit ("IC"), large resistors and capacitors are more difficult to manufacture than transistors. Consequently, IC designers have devised biassing techniques which use transistors wherever possible. In an IC, a constant current is often generated at one location and is distributed throughout the IC using current mirrors and steering circuits.

Biassing in IC design is often based on the well-known bandgap reference. A bandgap reference circuit takes advantage of a very stable delta base-to-emitter voltage (V_{BE}) between two conducting bipolar junction transistor ("BJT") to provide a constant current, which is then used as a reference current. In one such reference current, the voltage difference (ΔV_{BE} , typically approximately 60 mV) between two bipolar transistors' V_{BE} 's are applied across a known resistance to create a reference current. The reference current is then scaled by bias circuits to bias other circuits in the IC. To ensure that the reference current is stable across the integrated circuit, the bias circuits are fabricated within a set of tolerance and specifications matching those of the bandgap reference. For example, a bias circuit designed to operate with a 2 uA current source must be coupled to a bandgap reference which can accurately provide such a current.

In general, transistors fabricated on the same substrate can have matched characteristics which track changes in both the fabrication process and operating parameters (e.g., temperature). Manufacturing tolerances and design tolerances determine how closely circuits can be matched. If the design is sensitive to mismatches, manufacturing tolerance must be tightened. Otherwise, low production yield and device reliability would result. Circuit matching becomes more critical as bias currents reach the sub-nanoampere level, which is required in today's power devices.

The following equation relates in a BJT a change in voltage V_{BE} to a change in collector current:

$$\frac{I_{new}}{I_{old}} = e^{\frac{\Delta V_{BE}}{V_T}} \quad (1)$$

where I_{old} and I_{new} are the collector currents of a BJT before and after an increase of ΔV_{BE} in voltage V_{BE} ; and V_T (~26 mV) is the thermal voltage. Equation (1) can be rewritten as:

$$\Delta V_{BE} = V_T \ln \frac{I_{new}}{I_{old}} \quad (2)$$

Thus, equation (1) provides that a 60 mV change in V_{BE} results in a ten-fold increase in collector current. Similarly, equation (2) provides that an 8% change in collector current results in a 2 mV change in V_{BE} .

A low-current bias circuit 100 in the prior art is shown in FIG. 1. As shown in FIG. 1, circuit 100 includes transistors Q_8 and Q_9 of equal size, and resistor R_5 (180 KΩ) coupled

between an output terminal of current source 101 (which has a current I_{source} of 1 μ A) and the collector terminal (V_5) of transistor Q_8 . The base terminal of transistor Q_8 is also coupled to the output terminal of current source 101. The base terminal of transistor Q_9 is coupled to collector terminal (V_5) of transistor Q_8 . The collector terminal of transistor Q_9 is coupled to the circuit intended to be biased.

For our purpose, the base current of a BJT is negligible relative to the collector current. Thus, collector current I_{c8} of transistor Q_8 is equal to current I_{source} of current source 101. Since resistor R_5 provides a voltage drop of 180 mV from supply voltage V_{CC} , the V_{BE} of transistor Q_8 exceeds the V_{BE} of transistor Q_9 by 180 mV, thus output current I_{out} of transistor Q_9 is approximately 1 nA, as provided by equation 15 (1) above (i.e. $I_{out} = 10^{-6} \times e^{-180/26} = 0.984 \times 10^{-9}$). Circuit 100 can thus be used to supply a low bias current in an IC. Also, if circuit 100 is fabricated on the same substrate as the bandgap reference circuit which provides current source 101, circuit 100 tracks the bandgap reference over variations 20 in fabrication process and temperature.

Circuit 100, however, is sensitive to circuit mismatches. For example, if the resistance of resistor R_5 is lowered by 10% due to a variation in the fabrication process, the voltage across resistor R_5 decreases by 18 mV, which causes an 25 increase of the same magnitude in the V_{BE} voltage of transistor Q_9 . Consequently, the output current I_{out} of transistor Q_9 doubles. Thus, a 10% change in resistor R_5 results in a 100% increase in output current I_{out} . Clearly, such 30 match-sensitivity does not meet today's production yield and device reliability requirements.

Thus, a need for a low-current bias circuit that is relatively insensitive to circuit mismatches is desired.

SUMMARY OF THE INVENTION

The present invention provides a low-current bias circuit which is relatively insensitive to circuit mismatches. In one embodiment, a circuit of the present invention combines the effects of current degeneration, current gain, and voltage gain to minimize any errors caused by circuit mismatches 35 created during fabrication.

BRIEF DESCRIPTION OF THE DRAWINGS

The present invention may be better understood, and its 45 numerous objects, features, and advantages made apparent to those skilled in the art by referencing the accompanying drawings.

FIG. 1 shows a current bias circuit 100 in the prior art. FIGS. 2a to 2b show current bias circuits 200 and 250, 50 which illustrate different aspects of a circuit of the present invention.

FIG. 2c shows a circuit 280, which is an embodiment of the present invention.

FIG. 3 shows a spreadsheet for selecting component 55 values in one embodiment.

DESCRIPTION OF THE PREFERRED EMBODIMENTS

To facilitate comparison between elements of the various figures, and to simplify the detailed description below, like 60 elements in the various figures are provided like reference symbols or numerals.

FIG. 2a shows a current bias circuit 200. Current bias circuit 200 includes transistors Q_1 , Q_2 and Q_3 of equal size, and a current source 201. Current source 201 is coupled 65 between supply voltage V_{CC} and the commonly-connected

collector and base terminals of transistors Q_1 and Q_2 . The base terminal of transistor Q_3 is coupled to the collector terminal of transistor Q_2 , and the collector terminal of transistor Q_3 is coupled to supply voltage V_{CC} . The emitter terminals of transistors Q_1 , Q_2 , and Q_3 are coupled to a ground voltage reference.

In circuit 200, since transistors Q_1 and Q_2 have the same size, and their respective V_{BE} 's are the same, the current I_{source} ($\sim 2 \mu\text{A}$) of current source 201 is equally divided between the respective collector currents I_1 and I_2 of transistors Q_1 and Q_2 . (For our purpose, the base current of a BJT is negligible relative to the collector current). Thus, collector current I_2 of transistor Q_2 is approximately 1 μA . Since transistor Q_3 mirrors the current of transistor Q_2 , collector current I_{out} of transistor Q_3 also equals 1 μA .

Circuit 250 of FIG. 2b is substantially the same as circuit 200 of FIG. 2a, except that transistor Q_2 of circuit 200 is replaced in circuit 250 by transistor Q_4 , which is 10 times the size of transistor Q_1 ; also, resistor R_1 (60 $\text{K}\Omega$) is present in circuit 250. Resistor R_1 is coupled between the emitter terminal of transistor Q_4 and the ground reference. The size of transistor Q_4 and the resistance of resistor R_1 are selected so that collector current I_2 remains at approximately 1 μA . As can be seen from equation (1), a decrease of 60 mV in V_{BE} of transistor Q_4 results in a 10-fold decrease in I_2 , thus transistor Q_4 is sized to be 10 times the size of transistor Q_1 to offset the decrease in V_{BE} in transistor Q_4 . Thus, the resistance of resistor R_1 is selected to be 60 $\text{K}\Omega$, to result in a voltage drop of approximately 60 mV. Since transistor Q_3 mirrors the current of transistor Q_4 , the collector current I_{out} of transistor Q_3 remains at 1 μA .

FIG. 2C shows circuit 280, which is an embodiment of the present invention. Circuit 280 is substantially the same as circuit 250 of FIG. 2b, except that a 180 $\text{K}\Omega$ resistor R_2 is coupled between the output terminal of current source 201 and the collector terminal of transistor Q_4 . Since collector current I_2 of transistor Q_4 is 1 μA , the voltage across R_2 is 180 mV. Consequently, the V_{BE} of transistor Q_3 is 180 mV less than the V_{BE} of transistor Q_4 , so that a 1000 times decrease in the collector current I_{out} of transistor Q_3 results. In this case, current I_{out} becomes approximately 1 nA (1 $\mu\text{A}/1000$). Thus, circuit 280 of FIG. 2C provides a 1 nA bias current.

Low-current bias circuit 280 is relatively insensitive to circuit mismatches. For example, if the current I_{source} of current source 201 is 8% lower than 2 μA , an 8% change in collector current I_1 of transistor Q_1 results, which represents a 2 mV decrease in V_{BE} for transistor Q_1 , according to equation (2) above. Since the V_{BE} of transistor Q_1 is equal to the V_{BE} of transistor Q_4 plus the voltage drop V_1 across resistor R_1 , the 2 mV decrease in V_{BE} of transistor Q_1 is divided between the V_{BE} of transistor Q_4 and the voltage drop across resistor R_1 . Thus, in this example, because of R_1 's resistance and the size and the gain of transistor Q_4 , a decrease of 1 mV each is seen in the V_{BE} of transistor Q_4 and the voltage across resistor R_1 , and a net increase of 1 mV is seen at the collector terminal V_2 of transistor Q_4 , which is coupled to the base terminal of transistor Q_3 . Thus, the V_{BE} of transistor Q_3 is also increased by 1 mV, which results in a 4% increase in output current I_{out} of transistor Q_3 . Therefore, unlike a prior art circuit (e.g., circuit 100 of FIG. 1), which output current I_{out} varies by 100% for a 10% decrease in reference current I_{source} , circuit 280 of FIG. 2C provides a much more stable output current.

The component values shown for circuit 280 of FIG. 2C are chosen for illustration purposes only. For any given

application, components values and device ratios are chosen according to the invention illustrated above, and the constraints then prevailing. Component values can be affected, for example, by available die space and tolerance limits.

To select component values for circuit 280 of FIG. 2c, a designer would first set the most constricted parameter. In this case, the output and source currents are likely to be chosen first. The resistance of resistor R_2 is then selected to provide a V_{BE} of transistor Q_3 that would produce the desired output current. Initially, resistor R_1 is selected to provide transistor Q_4 a voltage gain of 3. For example, the resistance of resistor R_1 is selected to be 60 $\text{K}\Omega$, if resistor R_2 is selected to be 180 $\text{K}\Omega$. The size of transistor Q_4 can then be selected such that the resulting current gain from transistor Q_1 offsets the degeneration which results from the voltage drop across resistor R_1 , so as to result in substantially the same collector currents in transistors Q_1 and Q_4 . For example, transistor Q_4 is made 10 times larger than transistor Q_1 , if resistor R_1 is selected to be 60 $\text{K}\Omega$ and the expected collector current in transistor Q_4 is 1 μA . Similarly, transistor Q_4 can be made 100 times larger than transistor Q_1 if resistor R_1 is selected to be 120 $\text{K}\Omega$ and the expected collector current of transistor Q_4 is 1 μA .

After initial component values are selected, the designer can then adjust the component values to match specific requirements or design changes. For example, if output current I_{out} is adjusted, resistor R_2 is adjusted such that the degeneration on the V_{BE} of transistor Q_3 produces the desired output current. The resistance of resistor R_1 and the size of transistor Q_4 are then accordingly adjusted. Computer-aided design software is available to assist in the design process. For example, circuit simulation program SPICE and Microsoft Excel spreadsheets can be used. The use of computerized design tools is advantageous, since transcendental equations are often involved which solutions are obtained using numerical methods. Further, the interdependence of component values requires all values adjusted to be consistent with each other. FIG. 3 shows a sample Microsoft Excel ver. 5.0a spreadsheet which can be used to select component values for circuit 280 of FIG. 2c.

The above detailed description is provided to illustrate the specific embodiments of the present invention and is not intended to be limiting. Numerous variations and modifications within the scope of the present invention are possible. The present invention is set forth in the following claims.

What is claimed is:

1. A low current bias circuit comprising:
a first transistor having an emitter, a base, and a collector, the base of said first transistor being coupled to the collector of said first transistor;
a second transistor having an emitter, a base, and a collector, the base of said second transistor being coupled to the collector of said first transistor, the emitter area of said second transistor being larger than the emitter area of said first transistor;
a first resistor having a first end and a second end, the first end of said first resistor being coupled to the emitter of said second transistor, the second end of said first resistor being coupled to the emitter of said first transistor; and
a second resistor having a first end and a second end, the first end of said second resistor being coupled to the collector of said second transistor, the second end of said second resistor being coupled to the base of said second transistor;
whereby the current through the collector of said second transistor is substantially the same as the current through the collector of said first transistor.

2. The bias circuit of claim 1 wherein the emitter area of said second transistor is larger than the emitter area of said first transistor by a factor which offsets the degeneration brought about by the first resistor.

3. The bias circuit of claim 1 further comprising a current source coupled to the second end of said second resistor, wherein the amount of current supplied by said current source is approximately equal to the sum of the collector currents of said first and second transistors.

4. The bias circuit of claim 1 further comprising a third transistor having an emitter, a base, and a collector, the base of said third transistor being coupled to the first end of said second resistor, the emitter of said third transistor being coupled to the second end of said first resistor, the current through the collector of said third transistor being a fraction of the current through the collector of said second transistor.

5. The bias circuit of claim 4 further comprising a current source coupled to the second end of said second resistor, wherein the current supplied by said current source is provided to the collector of said first transistor and the collector of said second transistor but not to the collector of said third transistor.

6. A low current bias circuit comprising:

a first transistor having an emitter, base, and a collector, the base of said first transistor being connected to the collector of said first transistor;

a second transistor having an emitter, base, and a collector, the base of said second transistor being connected to the collector of said first transistor;

a first resistor having a first end and a second end, the first end of said first resistor being connected to the emitter

of said second transistor, the second end of said first resistor being connected to the emitter of said first transistor;

a second resistor having a first end and a second end, the first end of said second resistor being connected to the collector of said second transistor, the second end of said second resistor being connected to the base of said second transistor;

a third transistor having an emitter, base, and a collector, the base of said third transistor being connected to the first end of said second resistor, the emitter of said third transistor being connected to the emitter of said first transistor.

7. The circuit of claim 6 wherein the emitter area of said second transistor is larger than the emitter area of said first transistor.

8. The circuit of claim 7 wherein the current through the collector of said first transistor is substantially the same as the current through the collector of said second transistor.

9. The circuit of claim 6 wherein the emitter area of the second transistor is larger than the emitter area of the first transistor by a factor which offsets the degeneration brought about by the first resistor.

10. The circuit of claim 6 wherein the ratio of the resistance between the first resistor and the second resistor is substantially 1 to 3.

11. The circuit of claim 6 further comprising a current source coupled to the collector of said first transistor.
